HIS ATTORNEY.

UNITED STATES PATENT OFFICE.

RAGNAR O. BENSON, OF BROOKLYN, NEW YORK.

DESIGN FOR A PRINTER'S CUT OR DIE.

Application filed November 13, 1919. Serial No. 337,863. Term of patent 7 years.

To all whom it may concern:

Be it known that I, RAGNAR O. BENSON, subject of King Gustavus V of Sweden, residing in the borough of Brooklyn, county of Kings, in the city and State of New York, have invented a new, original, and ornamental Design for Printer's Cut or Die, of which the following is a specification, reference being had to the accompanying drawing, forming part thereof.

The figure is an enlarged view of an ornamental printer's cut or die for use in printing letterheads, envelopes and general stationery, according to my new design.

I claim,

The ornamental design for a printer's cut or die, as shown.

RAGNAR O. BENSON.
